UNITED STATES PATENT OFFICE.

PATRICK HARVEY, OF CHICAGO, ILLINOIS.

WATER-CLOSET.

SPECIFICATION forming part of Letters Patent No. 349,347, dated September 21, 1886.

Application filed October 19, 1885. Serial No. 180,253. (No model.)

To all whom it may concern:

Be it known that I, PATRICK HARVEY, a citizen of the United States, residing at Chicago, in the county of Cook and State of Illinois, have invented certain new and useful Improvements in Water-Closets, which are fully set forth in the following specification.

The invention relates to siphon water-closets, and has for its purposes, first, to provide a new means of exhausting the siphon by the flow of a current of water past the air-pipe leading from the siphon such that the flow of water for that purpose can be regulated according to the height and resulting pressure of the water, so that no more water shall be used for that purpose than is necessary; second, to prevent the air which is drawn from the siphon being discharged into the bowl and thence into the room, and to cause it instead to be discharged into the soil-pipe or sewer-pipe, whence it will pass through the usual ventilating-pipe to a ventilating-flue or to the outer air; third, to prevent any air which may at any time be driven from the siphon by the flow of water into it from the bowl being admitted into the bowl or by any course into the room, and to cause it instead to be forced into the soil-pipe and thence to escape into the ventilating-shaft.

In the drawings, Figure 1 is a vertical section of my improved water-closet and the tank and connections therewith. Fig. 2 is a horizontal section through x x on Fig. 1. Fig. 3 is a detail vertical section showing the adjustable mouth-piece of the air-pipe leading from the siphon.

- 30 A is the bowl.
- A' is the evacuating-siphon.
- A² is the lower trap.
- 40 A³ is the soil-pipe.
- A⁴ is the flushing-rim.
- B is the tank.
- B' is the service-box.
- C is the service-pipe which supplies the 45 tank.
- C' is the ordinary ball-cock which controls the supply of water to the tank.
- b is the valve which controls the flow of water from the tank to the service-box.
- 50 b' is the valve which controls the flow of water from the service-box to the closet. Both said valves are connected to the lever B², piv-

oted above the tank—one on one side the fulcrum and the other on the other side, so that one is opened when the other is closed. The 55 chain b', attached to the end of the lever B², is designed to be connected in any convenient and familiar manner with the closet seat, so as to be pulled down when the seat is depressed.

Thus far the construction is of a well-known form, and I will not describe it further in detail. The service-box B' has the portion B'', which may be a pipe communicating with the tank at the high water mark and open at the top, affording a convenient channel through 65 which to extend the connecting-rod b'', by which the lever b² actuates the valve b', and also constituting an air-vent for the service-box. The flushing-pipe E is inserted through the bottom of the service-box, and stands up 70 within the latter a short distance, E'. At the interior bottom of the service-box the pipe E has the apertures e e e, which will allow a limited flow of water from the service-box into the service-pipe. At the top of the siphon A', I 75 secure the box D, having at one end the nipple D', which makes a water-tight junction with the flushing-rim A⁴ at the aperture a', and having at the bottom the nipple D², which makes an air-tight junction with the siphon at the 80 aperture a'. At the back side box D has the nipple D³, to which the flushing-pipe E is connected. On the lower side near the end farthest from the bowl the box D has the nipple D⁴, to which is connected the pipe F, which 85 leads thence down behind the siphon and lower trap and discharges into the soil-pipe A³ at f beyond the lower trap, A².

Communication from the siphon A' to the pipe F is made through the duct d, made up as 90 follows: A short vertical pipe or duct, D²⁰, extends from said nipple up through the box D and opens on the upper side, the aperture D²⁰⁰ being closed by the plug or cap d²⁰⁰. Communicating with this duct D²⁰ at the side within the 95 box D is the horizontal duct or pipe D²¹, which leads to the short vertical duct or pipe D²², which is located at the end of the box D farthest from the bowl and opens at the top, the aperture D²²⁰ being closed by the plug or cap d²²⁰. Said pipe D²² terminates open a short distance 100 above the mouth d⁴ of the pipe F, with which it is concentric. It is interiorly screw-threaded and has screwed within it the collar d²², which

may be made to protrude below its lower end and constitutes therefore an adjustable extension of said pipe D². From the bottom or floor of the box D anywhere between the apertures a¹ and d⁴ are erected two partitions, D⁵ and D⁶, extending nearly to the top of said box and making water-tight junctions with both bottom and sides, and from the top of said box between the said partitions is suspended a similar partition, D⁷, reaching nearly to the bottom. These three partial partitions make a trap which prevents the passage of gas from the sewer or soil pipe back to the bowl or to the tank.

15 The operation of this entire device is as follows: When the chain b² is pulled down by the depression of the seat of the closet, or in any other manner, the valve b is opened and the valve b' is closed and the service-box fills.

20 When the chain b² is released, the valves are reversed, b being closed and b' opened, and the water from the service-box flows freely through the flushing-pipe E into the box D, and thence into the bowl, flushing the same, and also out through the pipe F, which is entered through the annular aperture between the end of the collar d²² and the aperture d¹. The portion of water which takes this latter course induces a suction of air from the siphon A', drawing it through the duct d made up of the pipes D²⁰ D²¹ D²², thus exhausting or rarefying the air in the siphon and causing it to evacuate the bowl. The water passing through F carries with it the air or gases drawn from the siphon and discharges into the soil-pipe. The air or gas mixed with the water while it is passing through the pipe F has an opportunity when it reaches the larger soil-pipe to separate, and then escapes through the 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

ing-pipe E causing the service-box to fill while the water is flowing from it to flush the bowl. It will be observed also that in either case the duct B' serves as an overflow from the tank to the service-box, and thence through the apertures e e to the flushing-pipe and the bowl, so that in case of any derangement in the ball-cock C preventing it from closing, the water will all pass through the closet into the sewer. For this purpose the total area of the apertures e e should be sufficient to allow the escape of as much water as the cock C can admit to the tank. It will be observed also that the pipe E should have a cross-section equal to that of the pipe F added to the area of the aperture a¹, in order that it may furnish enough water to both flush the bowl, (furnishing for that purpose as much water as the aperture a¹ will admit,) and also supply the pipe F, for the purpose of exhausting the air from the siphon. The amount of water required for the latter purpose will depend to some extent upon the speed of the current into the pipe F around the mouth of the duct d, and that speed will depend upon the height of the service-box above the closet or any other circumstance affecting the pressure. In order, therefore, that the device may be adjusted to the circumstances and the minimum quantity only of water used, I provide the collar d²², adjustable up and down from and toward the aperture d¹, to increase or diminish the area of access to the pipe F from the box D. To reach this collar and adjust it, the plug d²²⁰ is removed by a wrench and a screw-driver used to engage the collar d²² and screw it up or down.

In order that free access may be had to the pipe F to clear out any obstructions which may lodge therein, the pipe D²², forming the last section of the duct d, is made the full size of the pipe F. If necessary to give fuller access to the pipe F, the collar d²² may be screwed out at the top of the pipe D²². The trap formed by the partitions D⁵, D⁶, and D⁷ in the box D serves to prevent sewer-gas passing by way of the pipe F from the soil-pipe into the service-box, and thence into the room.

It is obvious that the box D may be removed from the closet and connected thereto by two pipes—one from the nipple D' to the aperture a¹ into the flushing-rim A', and another from the nipple D² to the aperture a' into the siphon; but by locating it, as illustrated, immediately above the siphon and against the bowl, the use of such pipes is made unnecessary. The box D is conveniently secured in place and tight connection effected by forming flanges H H on the top of the siphon, and flanges on the bottom of the box D, using rubber gaskets j j, slipped over the nipples D' and D², countersinking the apertures a¹ and a' to fit the nipples, respectively, and binding the box D to the closet by bolts through the flanges on both, having first forced the box laterally to crowd the nipple D' tightly into the countersunk aperture a'.

It is obvious that functionally the chamber of the box D is a part of the water-duct from the service-box to the soil-pipe, and also a part of the water-duct from the service-box to the bowl, and that said ducts merely meet and unite in said box, being one duct from said box to the service-box, and I do not limit myself to the particular structure of said two ducts which is here illustrated as involving said box; 5 but any structure involving the two ducts—one leading to the bowl and the other to the soil-pipe beyond the closet-traps, the latter being connected with the air-duct from the siphon, so as to exhaust it—would involve the 10 essence of my invention.

I claim—

1. In combination, substantially as set forth, the bowl, its siphonic evacuating-pipe and traps, and discharge-pipe to the sewer, the 20 water-ducts, one leading to the bowl and the other to the discharge-pipe beyond the traps, and the air-duct leading from the siphon into the latter water-duct, so as to be exhausted by the water-current through the same.
2. In combination, substantially as set forth, the bowl, its siphonic evacuating and discharge pipe, a water-pipe, an air-pipe from the siphon opening within the water-pipe, and an adjustable mouth-piece for said air-pipe, 25 whereby the water-aperture around said air-pipe may be regulated at will.
3. In combination, substantially as set forth, the bowl, its siphonic evacuating and discharge pipe, the box D, communicating with the bowl and with the siphon, the water-pipe E, leading into said box, the water-pipe F, leading out of said box, the air-duct d, leading from the siphon and terminating near to and concentric with the opening into said 35 pipe F.
4. In combination, substantially as set forth, the bowl, its siphonic evacuating and discharge pipe, the box D, communicating with

the bowl and with the siphon, the water-pipe E, leading into said box, the water-pipe F, 45 leading out of said box, the air-duct d, leading from the siphon and opening within the box D, having its terminal branch in line with the pipe F and its mouth near to the opening into said pipe, and provided with the aperture 50 D²²⁰ at the surface of the box D, and the interior collar, d²², constituting an adjustable mouth-piece accessible through the opening D²²⁰.

5. In combination, substantially as set forth, the bowl and its traps and discharge-pipe, the 55 water-pipe, and two water-ways supplied thereby, one leading to the bowl and the other leading to the discharge-pipe beyond the traps of the bowl, and having a trap to prevent return of gas from the sewer into the bowl or 60 service-box.

6. In combination, substantially as set forth, the bowl, its siphonic evacuating-pipe, traps and discharge pipe, the water-pipe and two water-ways supplied thereby, one leading to 65 the bowl and the other leading to the discharge-pipe beyond the traps of the bowl, and provided with a trap to prevent the return of gas from the sewer, and an air-pipe leading from the siphon and opening into the second 70 water-way beyond the trap therein.

7. In combination with the bowl and siphon made integral and having the apertures a' and a'', respectively, and the flanges H H, the box D, having the nipples D' and D'', to 75 fit said apertures, respectively, and the flanges H' H'', whereby it is secured to the bowl and siphon, substantially as set forth.

In testimony whereof I have hereunto set my hand, in the presence of two witnesses, at 80 Chicago, Illinois, this 14th day of October, A. D. 1885.

PATRICK HARVEY.
